PERMANENT MOLD MACHINE

Joseph L. Dostal, Birmingham, Mich., assignor to
 Eaton Manufacturing Company, Cleveland,
 Ohio, a corporation of Ohio

Application April 21, 1938, Serial No. 203,255

3 Claims. (Cl. 22—177)

This invention relates to permanent molds and to machines for use in connection therewith in the casting of molten metals, the principal object being the provision of apparatus of this type 5 of improved efficiency and construction.

Objects of the invention include the provision of a permanent mold apparatus, including a mold and associated structure, having provisions for the efficient cooling of the same whereby to enable the length of time between successive casting operations to be shortened; the provision of a permanent casting mold apparatus providing for the flow of air over the surfaces thereof heated in the casting operation in such a manner as 10 to efficiently dissipate the heat absorbed by the mold in the casting operation; the provision of a permanent mold apparatus as above described so constructed and arranged as to apply the cooling air first to that portion of the mold where 15 the concentration of heat in the casting operation is the greatest; the provision of an apparatus as above described having provisions for modifying the flow of cooling air into contact with the mold part to better accommodate the particular 20 size, shape and/or contour of the mold as governed by the parts to be cast therein; and the provision of a permanent mold apparatus arranged for the circulation of air over the rear 25 faces of the molds for the purpose of cooling the molds, in combination with suitable baffle means 30 adjustably related with respect thereto whereby to enable distribution of the air flowing through the mold to obtain optimum cooling conditions.

Other objects of the invention include the provision of means for supporting one part of a multi-part permanent mold structure so as to enable it to be readily advanced toward or retracted from a cooperating portion; the provision of power means for moving one portion of 35 a permanent mold into and out of cooperative relation with respect to another portion thereof together with means for supporting the movable portion of the mold for such movement in such a manner as to insure its freedom from binding or 40 the like during such movement; the provision of means for supporting one portion of a permanent mold for movement towards and from a cooperating portion and power means for effecting such movement, the connection with the power means 45 being such as to eliminate the necessity of accurate manufacture and assembly between the power means and the possibility of binding occurring because of wear of the supporting means; and the provision of a permanent mold including 50 a pair of separable portions and a cooperating

track, one of the mold portions being wholly supported on the track and being movable thereon into and out of cooperative relation with the other of said portions by power means.

Further objects of the invention include the provision of a permanent mold casting machine having certain new and novel features of construction; the provision of a permanent mold casting machine having a constant speed motor for effecting rotation thereof and means in the connection between the motor and the movable part of the machine enabling the rate of rotation of the machine to be varied at will; and the provision of a permanent mold casting machine particularly designed to permit a relatively high rate 15 of production thereby.

The above being among the objects of the present invention the same consists in certain novel features of construction and combinations of parts to be hereinafter described with reference 20 to the accompanying drawings, and then claimed, having the above and other objects in view.

In the accompanying drawings which illustrate a suitable embodiment of the present invention and in which like numerals refer to like parts 25 throughout the several different views.

Fig. 1 is a fragmentary top plan view of a permanent mold machine embodying the present invention;

Fig. 2 is a fragmentary vertical sectional view 30 taken axially through the permanent mold machine illustrated in Fig. 1;

Fig. 3 is an enlarged horizontal sectional view through one of the permanent molds and taken as on the line 3—3 of Fig. 2;

Fig. 4 is a vertical sectional view taken on the line 4—4 of Fig. 3;

Fig. 5 is a partially broken vertical sectional view taken on the line 5—5 of Fig. 4, showing one of the permanent mold parts in face elevation;

Fig. 6 is a vertical sectional view taken on the line 6—6 of Fig. 3;

Fig. 7 is an enlarged vertical sectional view taken on the line 7—7 of Fig. 1; and

Fig. 8 is a partially broken perspective view of 45 an article of the type formed by the particular conformation of the molds shown by way of illustration.

Permanent mold machines such as contemplated by the present invention comprises a relatively large generally circular supporting frame structure or turret suitably supported for rotation about its axis which is vertically disposed and provided with suitable means for rotating the same. At usually uniformly spaced stations ad- 50 55

5 jacent the periphery of the turret a permanent mold unit is provided and these units, of course, rotate with the turret. Each permanent mold unit includes a plurality, and usually two, mold sections which cooperate with each other to form 10 a complete mold structure. Hereafter in the specification and claims each permanent mold will be described as comprising a pair of halves, sections, or portions, this being mainly for the sake of simplicity in description as it will be understood that in some instances these molds may 15 comprise more than two parts in which case such changes from the construction shown and described as may be necessary to accommodate the same will be apparent to those skilled in the art. It will also be understood by those skilled 20 in the art that in the broader aspects of the present invention permanent mold units of the type provided by the present invention may be employed separately from a permanent molding machine of the type shown and described which includes a plurality of such units, as the novel features of the units, each of which includes molds and cooperating supports, themselves are 25 of advantage whether or not the units are arranged and operated singly or are arranged and operated in groups as herein described.

Each permanent mold comprises a relatively fixed part or half fixed with respect to the rotatable turret of a permanent mold machine of the type herein described although bodily rotatable therewith, and a cooperating part or half movable with respect thereto, the two parts cooperating with one another to form a mold cavity of the desired character between them. When such molds are employed in conjunction with a molding machine of the type herein described means are provided for maintaining the two halves of each mold in cooperating contacting relationship during a portion of each rotation of the turret and to separate the mold halves during another portion of each complete rotation of the turret. The molds are poured during that portion of each rotation of the turret when the halves are maintained in contact with each other and are separated from one another after the metal poured has solidified sufficiently to permit removal of the object cast from the mold without undue danger of distortion, and the halves are maintained in separated relation until a point in the rotation of the turret immediately preceding the point at which the molds are poured. Means are provided for automatically advancing and retracting the movable half of each mold 50 towards and from its cooperating half. Additionally the mold halves are each so constructed and cooperating means provided in conjunction therewith that air is caused to continually flow over the rear faces of the mold halves for the purpose of extracting the heat therefrom so as to prevent the molds from becoming over-heated, to effect a quicker solidification of the metal cast therein, and to permit operation of the machine at a greater speed than would otherwise be possible. The means thus provided will hereafter be described in detail later.

Referring now to the drawings and particularly to Figs. 1 and 2 the permanent mold machine there shown includes a suitable fixed supporting base or structure indicated generally at 10 and as provided with a fixed vertically extending cylindrical post or stub shaft 12. Rotatably mounted upon the post 12 is a drum-like member 14 which forms the central member of the rotatable turret and which is provided with a suit-

ably bushed central hub 16 which rotatably receives the post 12 for guiding the drum member 14 in its rotating movement. Suitable thrust bearing elements 18 disposed between the drum member 14 and the supporting base 10 serve to take the thrust of the turret.

A plurality of radially extending equally angularly spaced supporting arms 20 are rigidly secured to the peripheral surface of the drums 14 and project radially outwardly therefrom. At their outer ends the arms 20 are jointed by cord members 22 which thus serve to provide with the drum 14 and arms 20 a more or less circular radially spoked frame structure. The arms 20 are hollow and the hollow interiors are in open communication with the interior of the drum member 14. The upper end of the drum member 14 has suitably secured to its upper edge an annular plate-like member 24 which extends radially inwardly from the outer edge thereof. Adjacent its inner edge the plate member 24 has secured thereto and supports an upwardly extending circular housing 26 which housing is provided with an annular cored passage 28 therein serving as a distributing duct for compressed air as will hereinafter be more specifically brought out.

The upper end of the hub 16 of the drum-like member 14 is closed by a cap member 30 the interior of which is divided into completely separated upper and lower chambers by means of a cross-wall 32. Means such as the tube 34 are provided for introducing lubricant into the interior of the lower chamber so as to effect lubrication of the wearing surfaces of the post 12 and the thrust bearing 18. Suitable means such as the connection 36 communicating with the interior of the upper chamber in the cap 30 is suitably connected by means of a pipe line 37 (see Fig. 1) to the interior of the duct 28 in the member 26. Such upper chamber also communicates through the central upwardly extending connection 38 with a swivel joint 40 which is connected by a tube 42 with a suitable source of compressed air or suitable motive fluid. The air thus delivered through the pipe 42 passes through the swivel connection 40 into the upper chamber in the cap or cover 30 and then through the connection 36 and pipe line 37 to the interior of the annular conduit 28 in the member 26 to be there distributed through the various valves hereinafter to be described for use in the operation of the movable sections of the various permanent molds.

Suitably rotatably supported upon the upper end of the cap 30 is a spider 44 which terminates at its periphery in a ring 46 the lower edge of which is so constructed and arranged as to cooperate with the upper edge of the housing member 26 so as to minimize the leakage of air therebetween. The upper edge of the ring 46 is adapted to receive a stack or flue 48 through which air employed in the cooling of the mold may be withdrawn. It will be understood that the spider 44, ring 46 and flue or stack 48 remains stationary during rotation of the turret.

In order to rotate the turret the lower face of the drum member 14 has concentrically secured thereto an internal gear 50. A transmission mechanism including a casing 52 rigidly fixed with respect to the base 10 and a spur gear 54 lying in mesh with the gear 50 is employed for rotating the turret. The gear 54 is fixed upon a vertical shaft 56 rotatably mounted in the casing 52 and within which has fixed thereto a ring 75

gear 58. The ring gear 58 lies in mesh with a pinion 60 fixed upon the horizontally extending shaft 62 which is rotatably mounted within the casing 52 and one end of which projects therefrom and receives thereon a coupling member 64. The coupling member 64 is employed for connecting the shaft 62 to one element of a variable speed device of known construction including the elements 66 and 68 which are suitably connected together for equal rotation and in turn are adapted to be driven by the electric motor 70 of the synchronous or constant speed type. The motor 70 and speed reducing units 66 and 68 are fixed in suitably aligned relation upon a common base 72.

In accordance with the above description it will be appreciated that rotation of the motor 70 acting through the speed reducing units 66 and 68 and through the transmission including the gears 58 and 60 and gears 50 and 54 serve to rotate the turret, the speed of rotation of the turret being governed by the usual adjusting means provided in connection with the speed reducing unit 66—68. The necessity for adjusting the speed of rotation of the turret occurs as a result of the fact that it is always desirable to operate the turret at the highest speed possible consistent with the desired quality of work produced by the machine, this speed usually varying in accordance with the size of the particular articles being cast in the machine, the smaller the article the quicker it may be poured and the quicker it will cool to such an extent as to permit its discharge from the machine, as will be readily understood by those skilled in the art.

A mold assembly or unit, each including a pair of mold parts, supports and other elements aiding in providing a complete operative assemblage, is supported between the outer ends of each adjacent pair of arms 20, all of these assemblies or units being identical and the showing and description of one being sufficient as the showing and description of all. Each mold assembly includes a section fixed with respect to the turrets and a part movable with respect to the turrets and each mold proper includes, in the particular embodiment illustrated, a mold half 74 fixed with respect to the fixed section of the mold and a mold half 76 fixed with respect to the movable section of the mold, the mold halves 74 and 76 cooperating to form between them a depression or cavity 71 of the desired size, shape and contour desired in the particular article to be cast. The mold half 74 is fixed by means of bolts 78 to a vertically extending support indicated generally at 80 preferably formed integrally with the corresponding cord 22. Likewise the mold half 76 is fixed by means of bolts 82 to a support indicated generally at 84.

The support 84 is fixed as by bolts 86 to the upwardly extending flange 88 of a carriage including a pair of spaced parallel arms 90 arranged in generally radial relation with respect to the axis of rotation of the turret and the outer and inner ends of each of which each rotatably supports a grooved roller 92. The grooved rollers 92 at each side of the carriage 90 are received upon corresponding rails 94, the rails 94 being parallel and arranged with the center line between them in radial relation with respect to the axis of rotation of the turret. The rails 94 are supported from the arms 20 by means of a plurality of cross-bars 96 extending between and fixed to the lower faces of the cooperating pair of arms 20.

Each movable mold section including a support

84 and cooperating mold half 76 is thus arranged for bodily shiftable movement towards and away from the cooperating mold half 74 and support 82 and the entire weight of each movable mold section is carried by its corresponding carriage 90 which also serves as the sole means for guiding it through the major portion of its movement towards and from the fixed mold section. It is, of course, desirable, in order to insure positive alignment of the two mold halves 74 and 76 in their closed position in which they cooperate to receive a charge of molten metal, that usual or conventional dowel pins 98 fixed with respect to one of the mold halves and adapted to be slidably received by the other thereof, be employed in any case, and cooperate during the final closing movement of the die halves to accurately align one with the other.

The supports 80 and 84 are in the main substantially similar. In other words each has a substantially plane or flat operative face for co-operation with the corresponding mold half 74 or 76. Each is centrally provided with a relatively large approximately rectangular opening 100 therein as perhaps best brought out in Figs. 5 and 6. Each has a hollow chamber 102 formed along each side thereof of which chambers are connected at their lower ends by a hollow cross-chamber 104. Each side chamber 102 is provided with a vertically elongated opening 106 extending through the flat or operative face of the corresponding support.

Clamped between the flat or operative face of each support 80 or 84 and the cooperating mold halves 74 and 76 respectively is a preferably metallic sheet or plate 108 each of which is provided with a vertically elongated opening 109 therein corresponding and registering with each of the corresponding openings 106, and each plate 108 is provided with a vertically elongated central opening 110 therein of preferably greater width than the width of the side openings 109.

The back of each mold half 74 and 76 is hollow and except at its marginal edges is spaced from its cooperating plate 108 so as to form a passage-way 111 between each opening 110 and the cooperating openings 109 in each plate 108. While in the broader aspects of the invention it makes no difference whether the air employed for cooling the molds is forced through the molds under a positive pressure or whether it is drawn through the molds by sub-atmospheric pressure, the latter is preferable in that it aids in reducing the temperature of the air surrounding the molds and, accordingly, it will be assumed in the present case that the air for cooling the molds is drawn through the various passages therefor in the mold sections by suction.

In such case as above described it will be understood, and as will be hereinafter more fully described, that the cross-passage 104 in each mold section is connected to a suitable source of suction. In such event this suction will be transmitted from each cross-passage 104 to its cooperating side chambers 102, through the cooperating openings 106 in each of the supports and the cooperating openings 109 in the corresponding plate 108 to the space 111 between the corresponding mold half 74 or 76 and its support 80 or 84 respectively, and that the suction thus created within these spaces will cause air to be drawn through the central slot 100 in each of the plates 108, through the various passages described and into the cross-passages or chambers 104 from which it will be discharged. The air thus flowing

through the central passages 110 in the plates 108, in flowing over the rear faces of the mold sections 74 and 76 will extract heat therefrom thereby to effect a cooling of the mold halves. 5 The rate of heat extracted from the mold halves is preferably accelerated by providing a multitude of pins or fins 112 on the rear faces of the mold halves 74 and 76 and projecting into the path of flow of air over these rear faces.

10 In the cooling of molds by air as above described it is preferable that the cooling air in being delivered to the rear face of a mold half be initially directed at that portion of the mold half subject to the absorption of the greatest amount 15 of heat from the molten metal during a casting operation. While in the broader aspects of the present invention the construction is of such flexibility, as by providing any required number of openings 110 positioned as required to obtain 20 this effect as will hereinafter be more apparent, particularly where two or more objects are being cast simultaneously between each cooperating pair of molds, in the particular construction of the mold halves 74 and 76 shown by way of illustration, the mold halves 74 and 76 have been 25 formed to enable a single triangularly shaped pan-like member of the general character illustrated in Fig. 8 to be cast in the cavity 77 between them. The pan-like figure shown in Fig. 30 8 may be assumed, as a matter of illustration, to be suitable for use as a paving block for highways and the like, its upper or exposed surface being provided with a plurality of upwardly projecting ribs arranged in groups extending 35 transversely with respect to one another for the purpose of providing an anti-skid surface therefor.

It may also be assumed for the purpose of illustration that only one such block as illustrated 40 in Fig. 8 will be cast at one time between each pair of mold halves 74 and 76 and, accordingly, the depression or cavity 77 formed between the mold halves 74 and 76 will preferably be centrally located with respect thereto as illustrated 45 in the drawings. In such case the opening 110 being located centrally of each plate 108 will direct the flow of incoming air centrally with respect to each of the mold halves 74 and 76 and thus initially into that area of the mold halves 50 which will receive the greatest amount of heat from the molten metal received in the mold cavity 77. It will, however, be observed that with the particular conformation of the mold cavity 77 required to form the block shown in Fig. 8 the 55 greatest amount of metal in the mold cavity will be adjacent the lower edges thereof and, accordingly, the corresponding portions of the mold halves 74 and 76 will preferably receive a greater amount of cooling air than the upper portion 60 thereof which will be less highly heated in the casting operation. This effect is obtained in accordance with a further phase of the present invention which is particularly brought out in Figs. 3 and 5.

65 As indicated in Figs. 3 and 6 the above described effect is accomplished by the employment of a pair of baffle members 114 in connection with each opening 110. These baffle members 114 each comprise a plate-like member 70 cured to the outer face of each of the plate members 108 in cooperating relation with respect to the side edges of the opening 110. The plate members or baffles 114 are preferably readily adjustable with respect to the edges of the cooperating opening 110 so as to enable the effective

area and shape of the opening 110 to be varied. While any suitable means may be provided for adjustably supporting the baffle members 114 on their corresponding plate 108, one acceptable method is shown and which comprises the provision of slots 116 in the baffle members 114 and wing nuts 118 received on studs 120 fixed to the corresponding plates 108 and projecting through the slots 116. The studs 120 are sufficiently loosely received in the slots 116 as to permit the baffle members 114 to be moved bodily inwardly or outwardly in parallel relation with respect to the corresponding edges of the opening 110, or to be tilted with respect thereto as illustrated in Fig. 6, so as to cause, for instance, a greater restriction of the opening 110 adjacent the top thereof than at the bottom thereof. Preferably each of the baffle members 114 is provided at its inner edge with an outwardly extending flange 122, the flanges 122 preferably being curved outwardly 20 away from each other so as to provide a more or less venturi-like passageway between them more favorable to the flow of air therebetween without restriction.

In order to withdraw the air from the cross-chamber 104 in the stationary supports 80 a passageway 124, best illustrated in Figs. 1 and 7, is formed integrally with the cord 22 in communication with the cross-passage 104 and extends through and opens upon the joint between it and the adjacent cord 22. As best illustrated in Figs. 1 and 7 the cords 22 at adjacent ends are provided with vertically extending cooperating flanges 126 which are rigidly secured together by means of bolts 128. Below the flanges 126 the adjacent ends of the cords 22 are formed to provide a pocket 130 for relatively close reception of the end of the corresponding hollow arm 20. Within the pocket 130 the arm 20 is provided with an opening 132 which registers with the passage 40 124 and thus communication is established between the hollow interior of each arm 20 and the cross-passage 104 of a corresponding fixed support 80. It will be recalled that it has been previously explained that the hollow interior of 45 the arms 20 are in open communication with the interior of the central drum member 14 of the turrets.

As best illustrated in Figs. 2 and 4 the cross-passage 104 of each movable mold section 84 is in 50 open communication with the interior of a tube 134 which extends radially inwardly therefrom with respect to the axis of the turrets. Each tube 134 is fixed with respect to its corresponding movable mold section 84 and, as illustrated in 55 Fig. 2, its inner end projects relatively loosely through an opening 136 provided therefor at the inner end of the cooperating arm 20 and in the periphery of the drum member 14, so that the cross-passage 104 of each movable mold section 60 84 is communicated with the hollow interior of the drum 14.

From the construction of the central portion of the turret as heretofore described it will be understood that the hollow interior of the drum 65 14 is in open communication with the interior of the stack or flue 48 which is stationary. The stack 48 communicates with a suitable source of suction which may, for instance, be a suitable type of centrifugal fan (not shown) and which, when in operation, will maintain the interior of the flue 48 under a sub-atmospheric pressure of desired value. Accordingly, it will be understood that with the construction thus far described relatively cold or at least unheated air 70 75

will be drawn through the opening 110 in the plate member 108 of each of the mold sections 80 and 84, this air will bathe the inner surfaces of the mold halves 74 and 76, will then pass outwardly through the chambers 102 to cross-chambers or passages 104 and will then be drawn through the passages described to the interior of the drum member 114 and exhausted therefrom through the stack or flue 48. As it is preferable to permit this flow of cooling air to continue during the complete revolution of the turret in order to obtain a maximum cooling effect on the mold halves and thus aid in enabling the speed of production of the machine to be increased, no means are shown for interrupting this flow during any particular angular phase of movement of the turret.

As previously explained the movable mold section 84 is maintained in cooperating relationship with respect to the fixed mold section 80 during that phase of rotation of the turret during which the molten metal is cast into the mold cavity 77 and until a sufficient time has elapsed to insure the molten metal having solidified to such an extent as to make it feasible to open the mold and discharge the part thus cast from between them. The means for effecting this movement of each movable mold section towards and from its corresponding fixed mold section together with means so constructed and arranged as to effect such movement at the desired point in the path of rotatable movement of the turret, will now be described in detail.

As best shown in Figs. 1 and 2 a bracket member 140 extends between and is supported on the upper surfaces of each adjacent pair of arms 20 adjacent the central drum 14, and each bracket 140 is provided with an upstanding flange 142 to the rear face of which the forward end of an air cylinder 144 is fixed thereby to support the cylinder. The air cylinders 144 are of a conventional type each of which includes a piston 146 having fixed thereto a piston rod 148 which projects outwardly therefrom through the outer end of the cylinder 144 and flange 142. The cylinders 144 are so arranged that their respective piston rods 148 are arranged in radial relation with respect to the axis of rotation of the turret and so that the axis of each piston rod 148 extends centrally with respect to the radial center line of its corresponding mold assembly.

The movable section 84 of each mold assembly has fixed to its inward face as by means of screws 150 a yoke 152 and which, as best illustrated in Figs. 3 and 4, is provided with a central bore 154 arranged radially with respect to the axis of rotation of the turrets and in axially aligned relation with respect to the corresponding piston rod 148. The outer end of each piston rod 148 is provided with a peripheral flange 156 adapted to abut against the rear face of the corresponding yoke 152, and a projecting end portion 158 which projects through the corresponding bore 154 in loosely received relation. The outer end portion of the end 158 is shouldered to receive a washer 160 secured in place by means of a nut 162 threaded upon such outer end 158. The flange 156 and washer 160 are so spaced as to accurately receive the thickness of the corresponding portion of the yoke 152 therebetween and to permit the outer end of the corresponding piston rod 148 and appreciable amount of free play laterally in the bore 154 without permitting more than a very limited amount of play of the yoke 152 axially of the piston rod 148. This

arrangement insures that the entire weight of the movable mold section is carried on the rails 94 through the rollers 92 without endangering binding of the piston rod 148 in its cylinder.

A control valve structure of conventional construction indicated generally at 166 is provided for each cylinder 144 and is fixed with respect to its corresponding cylinder 144 in adjacent relationship upon the exterior surface of the central housing member 26. Each valve structure 166 is connected by means of a pipe line 168 with the forward end of the corresponding cylinder 144 and connected by a pipe line 170 with the rear end of its corresponding cylinder 144. Each valve is also provided with an air exhaust line or pipe 171 which, as shown in Fig. 2, discharges into the interior of the drum 14. The valves 166 are interiorly in communication with the annular duct 28 in the member 26 so as to receive a supply of compressed air therefrom. Each valve 166 is provided with an operating arm 172, the outer end of which supports a roller 174 as best shown in Fig. 2. As will be appreciated by those skilled in the art when the arm 172 is at one limit of its movable position compressed air from the duct 28 will be admitted to one end of the cylinder 144 while air will be permitted to escape from the opposite end thereof through the pipe 171, and when the arm 172 is at the opposite limit of its movable position the reverse of these conditions will obtain. As will also be appreciated, when air under pressure is introduced into the inner end of the cylinders 144 the corresponding pistons 146 will act through the corresponding piston rods 148 to move the corresponding movable mold sections radially outwardly with respect to the axis of the turrets and to place the mold sections in closed or pouring position, and that when compressed air is introduced into the forward end of each of the cylinders 144 and air is permitted to be exhausted from the rear end thereof the corresponding pistons will move rearwardly in the cylinders 144 and will cause the movable mold sections connected therewith to separate from the fixed mold sections so as to permit discharge of the article cast between such mold sections and conditioning of the mold sections for the next casting operation.

In order to effect an automatic actuation of the movable mold sections in properly timed relation to the rotatable position of the turret the following mechanism is provided. The stationary ring 46 which supports the stack 48 at the center of the turret is provided in its exterior surface with an annular T slot 180 therein. Secured to the outer face of the ring 46 by means of bolts 182 the heads of which are received within the T slots 180 is a pair of brackets 184 projecting radially outwardly from the ring 46. Each of the brackets 184 has secured to its lower face a cam member 186. The cam members 186 are secured to the brackets 184 by means of a pair of bolts 188 extending through a radial slot 190 in the corresponding bracket 186, the construction thus permitting the cam members 186 to be adjusted radially of their corresponding brackets 184. The cam members 186 as best shown in Fig. 1, have a V-shaped face or operating surface 192 for engagement with the rollers 174 on the operating arms 172 of the various valves 166. One of the cam members 186 is arranged so that its V surface 192 converges in a radially outwardly direction so that upon engagement with the roller 174 of any valve arm 172 the valve arm will be caused

to move to the outer limit of its movable position, and the other cam member 186 is arranged with its V surfaces 192 converging in an inwardly direction so that when it engages the rollers 174 of the valve arms 172 these arms will be caused to move to the inward limit of their movable position. By this means as the turret revolves and the various rollers 172 successively engage first one of the cam members 186 and then the other 10 cam 186 the valves will be operated first to effect a closing of the mold sections and then will be operated to separate the mold sections. The particular point at which the mold sections are opened or closed may be readily varied by simply 15 shifting the brackets 184 circumferentially of the ring 46, this being readily accomplished because of the manner of securing the brackets 184 to the ring 46 by the use of the T slots 180.

From the foregoing it will be understood that 20 in accordance with the present invention a permanent mold machine is provided in which means are provided for rotating the turret at different rates of speed although driven by an electric motor of constant speed, so as to accommodate 25 the machine to the highest rate of production commensurate with the size and characteristics of the article being cast; it provides a mold construction particularly useful in connection with a permanent mold machine but which may be 30 employed singly, if desired, and which because of its novel arrangement for artificially cooling the same permits unusual rapidity in repeated casting operations; and provides a novel arrangement for mounting and operating the various 35 movable mold sections in a permanent molding machine together with numerous novel details of construction throughout the same.

Formal changes may be made in the specific embodiment of the invention described without 40 departing from the spirit or substance of the

broad invention, the scope of which is commensurate with the appended claims.

What I claim is:

1. In combination, a permanent mold part having a recessed rear face, a member cooperating therewith to form a chamber bounded by the walls of said recess, said member having an opening therein for the flow of air into said chamber, and baffle means associated with said member operable to vary the effective area of said opening whereby to modify the flow of air through said opening. 5

2. In combination, a permanent mold part having a recessed rear face and a member associated therewith forming a chamber between it and said recessed face, said member having an opening therein for the flow of air into said chamber, a baffle carried by said member in cooperative relation with respect to the margins of said opening, and means cooperating between said baffle and member operable to adjustably secure said baffle in any one of a plurality of different positions on said member whereby to enable the effective shape and area of said opening to be varied by adjusting the overlapping relation of said baffle 20 with respect thereto. 15

3. In combination, a mold part having a recessed rear face, a member cooperating with said rear face whereby to form a chamber between it and said recessed face, said member having an opening therein for the flow of air into said chamber, baffle means adjustably secured to said member in cooperative and in partially overlapping relation with respect to said opening whereby to enable the effective shape and area of said opening 30 to be varied, and a flange on said baffle member for modifying the flow of air through said opening by forming a guiding means therefor. 35
